DESIGN FOR A COMBINATION COMB AND CURLER

Lawrence N. Johnson, Chicago, Ill.

Application April 7, 1938, Serial No. 76,359

Term of patent 3½ years

To all whom it may concern:

Be it known that I, Lawrence N. Johnson, a citizen of the United States, residing at Chicago, in the county of Cook and State of Illinois, have invented a new, original, and ornamental Design for a Combination Comb and Curler, as shown in the accompanying drawing, and described in the following specification.

The figure is a perspective view of a combi-

nation comb and curler showing my new design.

The other side of the combination comb and curler, not shown in the drawing, is substantially like the side shown, with the exception of the clip element, which is omitted.

I claim:

The ornamental design for a combination comb and curler as shown and described.

LAWRENCE N. JOHNSON.
